ATTORNEY

UNITED STATES PATENT OFFICE.

JOHN VAUDREUIL, OF MILWAUKEE, WISCONSIN, ASSIGNOR TO SANITARY DISHWASHING MACHINE COMPANY, OF MILWAUKEE, WISCONSIN, A CORPORATION OF WISCONSIN.

DISHWASHING MACHINE.

Application filed December 28, 1919. Serial No. 347,358.

The invention relates to liquid distributing apparatus and is here more particularly shown and described for use in a dish washing machine.

5 In order to distribute a spray over a large area it is the object of this invention to impart a rotary movement to the spray distributing member as said member moves in a circular path and at intervals reverse the 10 direction of movement in this circular path by tipping the spray nozzle. In this way the spray covers a large area and efficiently washes the dishes.

15 A further object of the invention is to provide a construction in which the spray nozzle is tilted automatically during its rotation and preferably by means of an unbalanced force.

20 A further object of the invention is to provide a construction in which the spray nozzle is automatically tilted by an unbalanced force produced by a part of the water being conducted to the nozzle.

25 The invention further consists in the several features hereinafter set forth and more particularly defined by claims at the conclusion hereof.

30 In the drawings Fig. 1 is a vertical sectional view through a dishwashing machine embodying the invention; Fig. 2 is a plan view of the distributor; Fig. 3 is an end view of the distributor; Fig. 4 is a section taken on the line 4—4 of Fig. 2.

35 The numeral 5 designates a casing having a bottom 6 and hooks 7 to support a removable cover 8 and a wire dish-supporting basket 9.

40 A distributor 10 is swiveled on a nipple 11 in the end of a pipe 12 forming part of a rotary support swiveled on a nipple 13 mounted on the end of a vertically disposed supply pipe 14 which projects up through the bottom 6 of the casing and is preferably located in the center of said bottom. Water 45 under pressure from the pipe 14 is conducted through the swivel joint between the pipes 14 and 12 to said pipe 12 and through the swivel joint between the pipe 12 and the distributor to a horizontally disposed 50 pipe 15 of the distributor.

55 In addition to the pipe 12 the rotary support includes a rod 16 having a weight 17 adjustably mounted thereon, the side of said support carrying said weight preferably counterbalancing the weight of the

other side of said support and the distributor carried thereby, though the weight may be adjusted to provide an unbalanced support if desired.

60 The pipe 15 of the distributor communicates with a nozzle member 18 having threaded engagement therewith so that it may be turned with respect thereto to change the angle of direction of the water issuing from the nozzle 19 on said member, said 65 nozzle 19 being inclined to either side of a vertical position during the operation of the device as hereinafter described.

70 The pipe 15 carries a rod 20 upon which arms 21 are swingingly mounted intermediate their ends, which arms are connected to small tanks 22 and 22'. These tanks 22 and 22' are connected together at their front ends by a member 23 which is connected to or formed integral with the nozzle member 18 so that the tipping of the tanks 75 tips the nozzle 19. The arms 21 and tanks 22 and 22' form a tiltable frame.

75 The tipping of the tanks together with the nozzle is accomplished by filling one tank 80 with more water than the other so that the weight of this tank produces an unbalanced force which causes the nozzle to tip laterally toward the side of the distributor carrying the then heavier tank. The tanks 22 and 85 22' are automatically filled during the operation of the device by conducting a portion of the water in the pipe 12 through a vertical hole 24 in said pipe and guiding it by a deflector 25 on each tank to an opening 90 26 in each tank from which it discharges in the tank then in raised position as shown in Fig. 4, while the excess of water in the lower tank has been allowed to escape through an outlet or drain 27 in that tank, 95 both tanks being provided with a similar drain.

100 The passage of water through the drains 27 of the tanks is automatically controlled by valve means here shown as being formed by a plate 28 centrally mounted on a pin 29 journalled in the rear arm 21, which plate is yieldingly held in engagement with the rear ends of the tanks 22 and 22' by means of a spring 30 mounted on the pin 29 and interposed between said arm 21 and a collar 31 carried by said rod. This plate 28 is shifted to alternately uncover the drains for the tanks 22 and 22' by means of a stop 32 secured to the rod 20 and having stop pro- 110

jections 33 and 33'. The tilting of the tanks is limited by a stop member 34 secured in vertical position upon the rod 20 and carrying a rubber bumper 35.

5 The weight of that portion of the distributor carrying the nozzle 19 is less than that on the other side of the swivel joint of said distributor but these weights may be made equal if desired. The overbalanced 10 relation of the distributor with relation to its support is desirable, however, as it produces a retarding effect upon the rotation of the distributor so that it rotates more slowly and thus distributes the water more efficiently.

A drain 36 is located near the bottom of the casing 5 to conduct waste water from the device.

With this construction if we consider that 20 the nozzle 19 has been tilted to one side of the vertical, then the action of the water issuing from the laterally disposed nozzle under pressure produces a rotary movement of the distributor in the opposite direction 25 upon the rotary support and at the same time it produces a rotary movement of the support in the same direction as that of the distributor, but since the distributor is eccentrically mounted with respect to its rotating support there are periods in the rotation of the distributor with respect to said 30 rotary support in which a retarding effect is produced upon the rotation of said support.

Thus, when the nozzle is turning from the 35 position shown in Fig. 1 to a position at right angles to the pipe 12 in a right-handed direction, a positive rotative impulse is imparted to the rotary support in that direction, but as it moves from this position inwardly toward parallel relation with the pipe 12 there is a retarding action imparted to the rotation of the rotary support. By this action the revoluble support is given a 40 jerky action with the rotating effect of the distributor together with its support predominating in one direction, which action allows the jet issuing from the nozzle 19 to play upon the dishes in the basket above for a longer period of time and covers a larger 45 area than would be the case if the distributor were directly mounted upon the supply pipe. This action takes place when the nozzle is disposed to either side of vertical position.

50 In order that after the rotary support has been rotated in one direction it may be reversed to rotate in the opposite direction, the nozzle 19 is first tipped to one side of the vertical and allowed to remain in this position for a certain period and is then automatically tipped to the other side of the vertical and remains in this position for a certain period. This is accomplished by filling one tank while draining the other.

55 Assuming that the parts are in the posi-

tion shown in Fig. 3, in which instance the nozzle 19 will be inclined toward the left, that is, toward the side carrying the lower tank 22', and the lowering of the tank 22' has moved the valve plate to a position to 70 bring it into engagement with the stop projection 33' and said plate has been swung to expose the drain opening 27 of the tank 22' and cover the drain opening 27 of the tank 22. Under these conditions water flows out 75 of the lower tank 22' and some water from the pipe 15 flows through the opening 24 into the tank 22, being directed through the opening 26 of that tank by the deflector 25 adjacent to said opening. As soon as enough 80 water has been admitted to the tank 22 to overbalance the tanks as shown in Fig. 4, then the heavier tank 22 moves the lighter tank 22' upwardly while it swings downwardly and the nozzle is swung toward the 85 right to inclined position, that is, toward the side carrying the then lower tank 22. During the downward movement of the tank 22 the plate 28 is moved out of engagement with projection 33' and into engagement 90 with projection 33, which then shifts the plate so that the opening 27 of the tank 22' is covered while the opening 27 of the tank 22 is opened. Then tank 22' fills up while tank 22 is draining until it becomes heavier 95 than tank 22 and moves down to the position shown in Fig. 3, shifting the valve plate 28 in the manner above described.

The reverse of the inclination of the nozzle depends upon the time it takes to fill one 100 tank with water enough to overbalance the other and during this time the distributor rotates upon and rotates the rotary support in one direction and then on a reversal of the nozzle the distributor rotates upon and 105 rotates the rotary support in the opposite direction. The extent of rotary movement of the rotary support in either direction depends upon the time required to effect tilting of the nozzle, and this time may be made 110 sufficient for only a partial rotation or for more than a single rotation of the rotary support upon the supply pipe.

I am aware that the reversal of the nozzle may be effected by other constructions differing specifically from that shown and I therefore desire it to be understood that this invention is not limited to any specific form or arrangement of parts except in so far as such limitations are specified in the claims. 115

What I claim as new and desire to secure by Letters Patent is:

1. In a liquid distributing device, the combination, with a supply pipe, a rotary support mounted thereon and having a pipe section communicating therewith, a rotary distributor eccentrically rotatably mounted on said support and having a pipe section communicating with the pipe section of said support, and means for conducting the liq- 120 125 130

- uid from the pipe section of the distributor to cause rotary movement of the distributor and rotary movement of said support in one direction for a predetermined period and then rotary movement of said distributor and rotary movement of said support in the opposite direction for a predetermined period.
2. In a liquid distributing device, the combination, with a supply pipe, a rotary support mounted thereon and having a pipe section communicating therewith, a rotary distributor eccentrically rotatably mounted on said support and having a pipe section communicating with the pipe section of said support and provided with a nozzle, and means for tilting said nozzle to either side of vertical position to rotate said distributor and also the support in reverse directions for certain periods.
3. In a liquid distributing device, the combination, with a vertical supply pipe, of a horizontally disposed support mounted to rotate on said pipe and having a pipe section communicating therewith, a horizontally disposed distributing pipe mounted on said pipe section beyond the center of said support and carrying a movable discharge nozzle which when directed laterally to either side of vertical position will permit the liquid issuing therefrom to rotate both the distributor and said support, and means for automatically tilting the nozzle to either side of vertical position during such rotation to reverse the direction of rotation of said distributor and support at predetermined intervals.
4. In a liquid distributing device, the combination, with a vertical supply pipe, of a horizontally disposed support mounted to rotate on said pipe and having a pipe section communicating therewith, a horizontally disposed distributing pipe mounted on said pipe section beyond the axis of said support and carrying a movable discharge nozzle adapted to be laterally inclined to permit the liquid issuing therefrom to rotate both the distributor and said support, and means for automatically tipping the nozzle to either side of vertical position by an unbalanced force to produce reverse rotations of said distributor and support.
5. In a liquid distributing device, the combination, with a source of fluid supply, of a rotary distributor including a pipe section communicating with said supply and provided with a nozzle movable with respect to said pipe section to a laterally inclined position to cause the liquid issuing therefrom under pressure to rotate the distributor, and means for reversing the inclination of the nozzle including a tank on each side of said nozzle and connected thereto, and means for alternately filling one tank while draining the other to produce an unbalanced force acting to tip the nozzle laterally toward the heavier tank at predetermined intervals.
6. In a liquid distributing device, the combination, with a vertically disposed supply pipe, a horizontally disposed fluid conductor mounted to rotate on said pipe, a horizontally disposed rotary distributing pipe eccentrically mounted on said conductor and carrying a nozzle movable with respect to said distributing pipe to a laterally inclined position, and means for reversing the inclination of the nozzle including a tank on each side of said nozzle and connected thereto, and means for alternately filling one tank while draining the other to produce an unbalanced force acting to tip the nozzle laterally toward the heavier tank at predetermined intervals.
7. In a liquid distributing device, the combination of a pipe provided with a nozzle movable with respect thereto to a laterally inclined position, and means for reversing the inclination of the nozzle including a tank on each side of said nozzle and connected thereto, each tank having a filling opening and a discharge opening, means for alternately conducting water from said pipe through the filling opening of the then elevated tank to tip the tanks, and valve means for controlling said filling and draining openings of said tanks.
8. In a liquid distributing device, the combination of a pipe provided with a laterally movable nozzle, and means for moving said nozzle comprising a tiltable frame connected to said nozzle and having tanks on opposite sides, each tank having a filling opening and a discharge opening, means for alternately admitting water to the tanks through the filling openings, valve means for controlling said discharge openings, and means for operating said valve means on the tilting of said frame.
9. In a liquid distributing device, the combination, with a supply pipe, of a horizontally disposed rotary support mounted thereon and having a pipe section communicating therewith, a rotary distributor eccentrically rotatably mounted on said support and having a pipe section communicating with the pipe section of said support, and means for conducting the liquid from the pipe section of the distributor to cause rotary movement of the distributor and rotary movement of the support in one direction for a predetermined period and then rotary movement of the distributor and rotary movement of the support in the opposite direction for a predetermined period, the distributor having an unbalanced mounting on said support whereby to retard the rotation of the distributor.

In testimony whereof, I affix my signature.
JOHN VAUDREUIL.
